UNITED STATES PATENT OFFICE

EDWARD F. AMENT, OF YOUNGSTOWN, OHIO

FURNACE DISCHARGING APPARATUS

Application filed March 1, 1930. Serial No. 432,499.

It is the usual practice to heat certain classes of material in furnaces into which the material is charged at one end and from which, after heating, it is removed at the other after having been gradually moved through the furnace while supported therein on suitable tracks. A typical example of a furnace of this character and operated in accordance with this practice is the usual pair 10 heating furnace used for heating "pairs" or steel bars preparatory to their being rolled into sheets.

In the normal operation of such furnaces the pairs or other material to be heated are 15 consecutively placed either singly or a few at a time on a charging platform in front of the charging door of the furnace and then consecutively pushed into the latter by means of a pushing mechanism having a stroke 20 which is relatively short compared to the total travel of the pairs through the furnace from one end thereof to the other. Thus, so long as more and more pairs are fed into the furnace, those which were previously introduced and which form a column or stack extending towards the drawing door are gradually pushed forward with a step-by-step motion until they are sufficiently adjacent thereto to permit them to be successively re- 25 moved by the operator.

From time to time it becomes necessary in the operation of such a furnace to completely empty it of the material which is being heated, either to facilitate repairs or because the furnace is to be shut down for an extended period. Thereupon the feed of the pairs to the furnace is discontinued and the pairs in the furnace which lie on tracks or skids extending therethrough are pushed forward 30 as far as possible by means of the pusher, but of course as the stroke of the latter is limited, it then becomes necessary to introduce some spacing means between the pusher and the hindmost pair to enable it, as well as 35 the preceding pairs remaining in the furnace, to be moved up adjacent the drawing door for removal by the operator with consequent emptying of the furnace. It has therefore been the practice heretofore to provide a 40 series of metallic frames or spacers each of

suitable size to be introduced, when the pusher is retracted, between the pushing apparatus and the hindmost pair after it has been pushed into the furnace, so that on the ensuing forward stroke of the pusher the 55 column of pairs in front of the spacer will be moved forward for a limited distance; thus, by introducing the spacers successively one after the other, it is possible to progressively push the column toward the drawing 60 door until the hindmost pairs reach a position from which they may be removed by the operator. This practice is, however, open to numerous objections, among which may be mentioned the usual necessity of leaving the 65 series of spacers in the furnace after the pairs are ejected therefrom until they can be progressively pushed out by feeding in new pairs between the pusher and the hindmost spacer upon a resumption of the heating operation and this subjection of the spacers to the heat of the furnace frequently results in their becoming so warped out of shape as to prevent their subsequent use. Moreover, as the spacers are introduced at the charging 70 end of the furnace, there is no way of thereafter guiding them along the skids and they therefore often ride to one side of the skids or the other and cause the material in the furnace, and sometimes even the pusher itself, to ride off the skids and follow the sides of the furnace, necessitating the cooling of the furnace to get the material out of it or otherwise interfering with its normal operation. For these as well as other reasons, such 75 as the cost of the spacers and necessity of frequently renewing them, the labor and annoyance involved in their use and the room which they take up in the vicinity of the furnace or at some other point in the plant when 80 they are idle, makes the employment of the spacers extremely undesirable but heretofore, so far as I am aware, no satisfactory substitute has been suggested therefor.

The present invention, therefore, has for 95 its principal object the provision of means for discharging or emptying the furnace not open to the objections inherent in the spacers or the like devices heretofore utilized therefor and which, additionally, embody advantages 100

such as convenience and certainty of operation, saving of time, positive action and low cost which enhance the desirability of their employment.

8 A further object of the invention is the provision of an apparatus of the character aforesaid adapted for operative combination and association with the ordinary pusher mechanism of the furnace and which, when 10 its use becomes necessary or desirable, may be readily placed in position and thereafter operated to empty the furnace with a minimum expenditure of time and effort.

15 A still further object of the invention is the provision of furnace discharging apparatus of novel character and which is adapted for use with substantially any type of furnace in which the material to be heated is pushed through the furnace from one end to 20 the other, as well as to provide an apparatus of this character which is relatively simple, inexpensive and of such form and construction that it is not liable to get out of order or become damaged under the conditions of use 25 to which it must necessarily be subjected.

30 Additional objects, advantages and novel features of design, construction and arrangement comprehended by the invention are hereafter more particularly mentioned or will 35 be apparent to those skilled in the art from the following description of one embodiment thereof as illustrated in the accompanying drawings in operative combination and association with a furnace and its pusher mechanism.

40 In the said drawings, Figure 1 is a horizontal section through the furnace (which in this figure is foreshortened for convenience of illustration) substantially on the line 1—1 in Fig. 3, the discharging apparatus being shown as it appears shortly after being placed in operative position after the feeding of the pairs to the furnace has been arrested preparatory to emptying the latter; Fig. 2 45 is a similar view but showing the entire length of the furnace and the parts of the discharging apparatus as they appear after all or substantially all of the pairs have been removed from the furnace and Fig. 3 is a vertical section through the furnace substantially on the line 3—3 in Fig. 2. Figs. 4 to 50 12 inclusive are fragmentary enlarged detail views of different parts of the apparatus, Fig. 4 being a top plan view of the rear of the pusher cylinder and adjacent parts, and Fig. 5 a rear end view thereof. Fig. 6 is a top plan view of the guide plate and adjacent parts showing the plate secured in operative position on the pusher platen of the pusher 55 mechanism; Fig. 7 is a rear elevation of the guide plate removed from the pusher platen and Fig. 8 is a vertical section through the guide plate substantially on the line 8—8 in Fig. 7. Fig. 9 is a top plan view of one end 60 of the auxiliary pusher platen and adjacent 65

parts; Fig. 10 an end elevation thereof and Fig. 11 a rear elevation thereof, while Fig. 12 is a transverse section through the auxiliary pusher platen substantially on the line 12—12 in Fig. 11. In Fig. 13 I have shown a slightly different form of pusher mechanism embodying a vertical platen as well as a modified form of guide plate which may desirably be employed therewith. The same characters of reference are used to designate the same parts in the several figures.

70 As the furnace and pusher mechanism in connection with which the discharging apparatus is employed form no part of the present invention and may be of any preferred construction, I have only shown in the drawings such parts of a typical furnace and pusher mechanism as are requisite for an adequate comprehension of the invention. Thus, the furnace may comprise the usual 80 side walls 1, front and rear walls 2, 3, roof 4 and hearth 5 above which on suitable supports 6 is disposed a pair of laterally spaced skids or tracks 7 extending through the furnace from the charging door opening 8 to the drawing door opening 9 which are 85 respectively adapted to be operatively closed by a charging door 10 and a drawing door 11, a flue 12 communicating with a stack 13 being provided for exhausting the products 90 of combustion in the usual way.

95 In front of the furnace the pusher mechanism, generally designated as M, is disposed on a pedestal 15, said mechanism comprising in the customary way a hydraulic or other cylinder 16 having a piston disposed therein 100 whose piston rod carries at its forward end the usual pusher platen 17 which, as shown, is upwardly and rearwardly inclined so that the pairs will be pushed into the furnace in a correspondingly inclined position to thereby 105 prevent them from falling over forwardly. The pusher platen is wide enough to overlie the adjacent ends of the skids 7 which are desirably projected through the charging door opening to extend alongside of the pusher mechanism and thus form in effect a charging platform on which the pairs may be disposed preparatory to pushing them 110 into the furnace by a forward movement of the pusher platen. As pusher mechanism of the general character of that to which reference has just been made is commonly employed in connection with pair heating and like furnaces, further reference thereto would 115 be superfluous.

120 It will thus be understood that in the normal operation of the furnace the pairs, either singly or a few at a time, are consecutively disposed on the skids or charging platform between the charging door opening and the pusher platen when the latter is retracted and then, after the charging door 10 is raised, 125 are pushed into the furnace by suitable actuation of the pusher mechanism until finally a 130

column or stack of pairs or other material P is formed on the skids extending from a point near the charging door to a point near the drawing door through which the leading and 5 fully heated pairs are thereafter consecutively removed by the operator at that end of the furnace as fresh pairs are fed in at the charging end.

As above explained, the present invention 10 is designed to provide means for pushing through the furnace the pairs which have been previously fed thereinto after the feed of fresh pairs is discontinued to thereby facilitate the emptying of the furnace. To 15 this end and in accordance with the invention, I provide an auxiliary pusher platen generally designated as 20 and best shown in Figs. 9 to 12 inclusive, which comprises a plate 21 of sufficient length to overlie the 20 skids 7 and project beyond them in either direction for a suitable distance; as shown, this plate is disposed vertically but, if desired, it may be inclined rearwardly and upwardly similarly to the pusher platen 17. 25 The plate 21 is desirably provided along its upper edge with a rearwardly extending flange 21', and adjacent each end of the plate beneath the flange is disposed a cylindrical socket 22 adapted to receive the end 30 of a plunger 23 which extends rearwardly therefrom. These sockets are desirably spaced apart laterally for a distance somewhat in excess of the distance between the skids, so that when the apparatus is in position the plungers 23 which may desirably be made of pipe project rearwardly from the auxiliary platen in parallel relation with the skids on either side thereof. For supporting the auxiliary platen on the skids and 35 decreasing its frictional resistance to movement therealong, a roller 24 of sufficient length to overlie the skids is desirably provided and journaled for rotation in brackets 25 bolted or otherwise secured to the rear 40 face of the plate 21, the roller being so disposed as to extend a little below the lower edge of the plate to thereby maintain the latter in spaced relation to the skids when the roller is resting thereon. 45 The plungers 23 are somewhat longer than the overall length of the furnace so that when the apparatus is in operative position, they will extend from the auxiliary pusher platen 50 through the charging door opening 8 and on either side of the pusher mechanism M as best shown in Figs. 1 and 2. For guiding the plungers as well as for affording means for communicating the motion of the pusher platen thereto, a guide plate 30, as best shown 55 in Figs. 6 and 7, is provided; this plate is of substantially the same length as the plate 21 and is bored adjacent its ends for the passage of the plungers, the diameter of the openings 31 thus formed in the plate 60 being somewhat greater than that of the

plungers so as to afford suitable clearance around the latter. On its forward side the plate is provided with two pairs of spaced brackets 32 between each of which is journaled a small roll 33 adapted to support the 70 superjacent plunger in coaxial relation with the adjacent opening 31, and the plate between the rolls is drilled for the passage of bolts 34 by means of which it may be removably secured to the platen 17 of the 75 pusher mechanism which is correspondingly bored for the reception of the bolts. The guide plate 30 is preferably disposed at right angles to the plane of the skids and thus normal to the axes of the plungers; thus, where, as is quite usual, the pusher platen is rearwardly and upwardly inclined as shown in Fig. 3, a plurality of spacer blocks 35 having correspondingly inclined rear faces may be welded or otherwise secured to the back 80 of the guide plate 30 so as to hold the latter in the proper position when the inclined faces of the blocks are seated against the correspondingly inclined face of the platen. However, when the platen 17' is vertically 85 disposed as shown in Fig. 13, the spacer blocks 35' may have their rear faces parallel with the front face of the guide plate or else may be omitted entirely and the plate bolted directly to the pusher platen. 90

Suitable means are also provided for affording support to the rear ends of the plungers when the latter are retracted as shown in Fig. 1, said means preferably comprising a roller 40, of sufficient length to allow the plungers to overlie it, disposed transversely of the latter at any suitable point adjacent the rear end of the pusher mechanism. A convenient method of mounting the roller is by means of oppositely formed brackets 41 secured by bolts 42 to the flange of the rear cylinder head of the pusher mechanism, these brackets being arranged to receive the shaft of the roll as best shown in Figs. 4 and 5 at a proper height to afford the requisite 100 support to the plungers, but any other method of mounting the roller may be utilized if preferred. The brackets and roller 40 after being placed in position may thereafter be left 105 permanently therein. 110

The plungers are provided at spaced intervals with vertically extending holes 43 for the reception of removable headed pins 44 which can be slipped into the holes in advance of the guide plate so as to receive the 115 thrust thereof as it is advanced by the pusher mechanism to thereby in turn advance the plungers and the auxiliary pusher platen relatively to the furnace. 120

While it is believed the method of employing my improved furnace discharging apparatus will be apparent from the foregoing description and the drawings forming part of this specification, brief reference thereto may not be out of place: The normal operation of 125

the furnace is carried on as usual until it is desired to empty it. Thereupon, the feed of fresh pairs through the charging door opening is discontinued and the pusher mechanism is operated so as to push the hindmost pair *p* which has been previously fed into the furnace as far forward as possible. Furnace discharging apparatus constructed in accordance with my invention is then brought up and the guide plate 30 bolted in position on the pusher platen while the latter is retracted so that the auxiliary platen 20 lies between the guide plate and the hindmost pair. The rear ends of the plungers thus extend over and are supported on the roller 40 and the former may then be pushed forward so as to bring the auxiliary platen 20 into engagement with the hindmost pair *p*. Pins 44 are next inserted in the transversely aligned holes in the plungers which lie in front of and nearest to the guide plate and the pusher mechanism then operated so as to move the guide plate and in turn the plungers and auxiliary platen forwardly into the furnace, thus pushing the column of pairs forwardly until the pusher mechanism reaches the extremity of its forward stroke. The pusher platen and guide plate are then retracted by suitable actuation of the pusher mechanism, but owing to the clearance between the walls of the openings 31 in the guide plate and the plungers, the latter do not move back with the guide plate but remain in their forwardly projected position. When the pusher platen and guide plate reach the limit of their rearward stroke, the same or other pins 44 are inserted in another pair of aligned holes in the plungers in front of the plate and as closely adjacent thereto as convenient and the platen and plate again moved forwardly, with corresponding forward movement of the plungers and auxiliary platen which is communicated through the latter to the column of pairs lying on the skids to move them forward to a corresponding distance. This series of operations are consecutively repeated until the auxiliary platen reaches substantially the position shown in Fig. 2, thereby bringing the hindmost pair to a position *p'* from which it may be readily removed through the drawing door, thus entirely clearing the furnace of material. The pins 44 are now removed from the pipes and the latter retracted by hand or otherwise until the auxiliary platen passes through the charging door opening and entirely clears the same, after which the guide plate is unbolted from the pusher platen 17 and the discharging apparatus, except the roller 40 and its support, removed until again required for emptying the furnace a second time.

It will thus be apparent that in accordance with my invention I have provided apparatus for pushing the pairs or other material through the furnace which is positive in ac-

tion and so constructed as to properly follow the skids and correspondingly cause the material to similarly follow them throughout its passage therealong; that the apparatus is of such character as to permit it to be very readily put into use when and as required and as readily removed from operative position when no longer needed, so that it is entirely unnecessary to leave any portion of the apparatus in the furnace after it has been emptied of material and while it is cooling down. In consequence, the apparatus is not subjected to such prolonged heating as would tend to cause warping or disalignment of the parts, and as the actual operative wear of the latter is substantially negligible, the apparatus remains in serviceable condition substantially indefinitely, thus avoiding the expense of frequent replacement which is one of the objections to the frames or spacers heretofore employed when emptying a furnace. Moreover, as the apparatus is of relatively simple form and construction, its initial cost is relatively low and as the parts are strong and devoid of delicate mechanism, there is but little danger of their becoming damaged or getting out of order under the conditions of use to which they are necessarily subjected.

While I have herein described one form of my invention with considerable particularity, I do not hereby desire or intend to specifically confine myself to any specific details in the design, construction and arrangement of the various parts as, if desired, the same may be varied in numerous particulars in accordance with the particular conditions under which the apparatus is to be used or to adapt it for employment with different types of furnaces and/or pusher mechanism or for other reasons without departing from the spirit and scope of the invention as defined in the appended claims.

Having thus described my invention, I claim and desire to protect by Letters Patent of the United States:

1. Apparatus of the character described, comprising a pusher platen adapted to extend transversely of the skids in a furnace, spaced plungers extending rearwardly from the platen, and a guide plate adapted for operative connection with the pusher platen of the furnace charging mechanism and provided with spaced openings for the passage of the plungers.

2. Apparatus of the character described, comprising a pusher platen adapted to extend across the skids of a furnace, means for supporting the platen in spaced relation to the skids, a pair of laterally spaced plungers carried by and extending rearwardly from the platen, and a guide plate adapted for operative attachment to the pusher platen of the furnace charging mechanism and having spaced openings for the passage of the plungers.

ers and means adjacent each opening for affording support thereto.

3. Apparatus of the character described, comprising a pusher platen adapted to extend transversely across the skids of a furnace, antifriction means carried by the platen operative to support the same in spaced relation with the skids and facilitate its movement therealong, a pair of laterally spaced plungers carried by and extending rearwardly from the platen, and a guide plate adapted for operative attachment to the pusher platen of the furnace charging mechanism and having laterally spaced openings for the passage of the plungers and antifriction means disposed adjacent each opening to afford support to the plunger when extended therethrough.

4. Apparatus of the character described, comprising a pusher platen adapted to extend transversely across the skids of a furnace, a roller carried by the platen operative to support the same in spaced relation with the skids and facilitate its movement therealong, a pair of laterally spaced plungers carried by and extending rearwardly from the platen, a guide plate adapted for operative attachment to the pusher platen of the furnace charging mechanism and having laterally spaced openings for the passage of the plungers and a roll disposed adjacent each opening to afford support to the superjacent plunger when extended therethrough, and means for supporting the ends of the plungers when retracted through the guide plate.

5. Apparatus of the character described, comprising a pusher platen adapted to extend transversely across the skids of a furnace, a roller carried by the platen operative to support the same in spaced relation with the skids and facilitate its movement therealong, a pair of laterally spaced plungers carried by and extending rearwardly from the platen, a guide plate adapted for operative attachment to the pusher platen of the furnace charging mechanism and having laterally spaced openings for the passage of the plungers and a roll disposed adjacent each opening to afford support to the superjacent plunger when extended therethrough, and means carried by the guide plate operative to maintain it at right angles to the plane of the skids when operatively attached to the pusher platen of the charging mechanism.

55. 6. The combination with a furnace having spaced skids extending therethrough and charging mechanism comprising a pusher platen disposed adjacent the charging door of the furnace, of means for moving material along said skids comprising a guide plate secured to the pusher platen of said mechanism, a pair of plungers disposed on opposite sides of the skids and respectively guided by the plate, an auxiliary pusher platen secured to the forward ends of the

plungers and extending transversely of the skids, and means for imparting to the plungers forward motion of the pusher platen induced by actuation of the charging mechanism.

7. The combination with a furnace having laterally spaced skids extending longitudinally therethrough and charging mechanism comprising a pusher platen disposed adjacent the charging door of the furnace, of means for communicating to material on the skids within the furnace forward motion of the pusher platen induced by actuation of the charging mechanism and comprising an auxiliary pusher platen adapted to engage said material, laterally spaced plungers extending rearwardly from said platen, a guide plate operatively secured to the pusher platen of the charging mechanism so as to move therewith and having openings for the passage of the plungers, and means removably secured to the plungers adapted for engagement by the guide plate to thereby transmit motion of said pusher platen thereto.

8. The combination with a furnace having laterally spaced skids extending longitudinally therethrough and charging mechanism comprising a pusher platen disposed adjacent the charging door of the furnace, of means for communicating to material on the skids within the furnace forward motion of the pusher platen induced by actuation of the charging mechanism and comprising an auxiliary pusher platen extending transversely of the skids and having antifriction means adapted to rest thereon to facilitate movement of the platen therealong, laterally spaced plungers extending rearwardly from the platen on opposite sides of the skids and charging mechanism, a guide plate operatively secured to the pusher platen of said mechanism and comprising spaced openings adapted for the passage of the plungers, means carried by the guide plate for affording vertical support to the plungers when extended through said openings, and removable means adapted for disposition at spaced points along the plungers for engagement by the guide plate when moved forwardly by the pusher mechanism to thereby impart corresponding movement to the plungers and auxiliary platen.

9. The combination with a furnace having laterally spaced skids extending longitudinally therethrough and charging mechanism comprising a pusher platen disposed adjacent the charging door of the furnace, of means for communicating to material on the skids within the furnace forward motion of the pusher platen induced by actuation of the charging mechanism and comprising an auxiliary pusher platen adapted to engage said material, laterally spaced plungers extending rearwardly from said platen, a guide

plate operatively secured to the pusher plate of the charging mechanism and having openings for the passage of the plungers, and means for supporting the rear ends of the plungers when extended through the guide plate for a predetermined distance.

In witness whereof, I have hereunto set my hand this 26th day of February, 1930.

EDWARD F. AMENT.
